UNITED STATES PATENT OFFICE.

JOHN F. ENSMINGER, OF TOLEDO, OHIO.

COMBINED SEAM-STRENGTHENER, GUSSET, AND FLY.

SPECIFICATION forming part of Letters Patent No. 298,360, dated May 13, 1884.

Application filed January 3, 1884. (No model.)

To all whom it may concern:

Be it known that I, JOHN F. ENSMINGER, a citizen of the United States, residing at Toledo, in the county of Lucas and State of Ohio, have invented certain new and useful Improvements in Combined Seam-Strengtheners, Gusset, and Fly, of which the following is a specification, reference being had therein to the accompanying drawings.

10 This invention has relation to improvements in pantaloons and overalls; and it consists in the peculiar construction of a combined gusset, seam-strengtheners, and button-hole fly, as will be hereinafter more fully set forth, and 15 particularly pointed out in the claims appended.

The invention has for its object to provide a cheap and simple means for strengthening the weakest portion of pantaloons, overalls, 20 and drawers, or that portion which is most liable to break or have the seams rip, and also to provide, in connection with said device, a fly for either the buttons or button-holes. These objects I accomplish by the means shown 25 and illustrated in the accompanying drawings, in which—

Figure 1 is a face view of a pair of pantaloons with the front portion let down to show the back-seam strengthener applied, and Fig. 30 2 a plan view of the blank constituting my invention.

Referring by letter to the drawings, A indicates a pair of pantaloons or overalls, and B the blank from which is formed the button-hole fly and gusset. From the gusset *a* are 35 opposite extensions, *b b*, which extend a suit-

able distance down the inner seams of each leg from the crotch, and may be secured by the same threads that make the leg-seams. About midway the gusset, and angular to the extensions *b b*, is a rearward extension, D, which is designed to extend up the back-seam of the garment to which it is applied, to or within a short distance of the waistband, and directly opposite this extension is a double extension, E, 45 which is designed to be folded as indicated in dotted lines, and form the button-hole fly. By this construction it will be seen that a crotch-gusset, button-hole fly, and strengthener is formed from a single piece of material. 50

I am aware that it is not new to provide pantaloons with a gusset having prolongations for strengthening the seams, and therefore do not claim such, broadly; but

What I claim as new, and desire to secure 55 by Letters Patent, is—

1. A combined gusset, seam-strengtheners, and button-hole fly for pantaloons, substantially as specified.

2. The combination, with the pantaloons, of 60 the gusset *a*, having extensions *b b*, for strengthening the inner seams of the legs, the rearward extension, D, for strengthening the back-seam, and the forward extension, E, for strengthening the front seam, and forming the button or 65 button-hole fly, substantially as specified.

In testimony whereof I affix my signature in presence of two witnesses.

JOHN F. ENSMINGER.
